REFRIGERATION SYSTEM

Herbert D. Euwer, St. Louis, Mo., assignor to
 American Car and Foundry Company, New
 York, N. Y., a corporation of New Jersey

Application February 27, 1939, Serial No. 258,622

10 Claims. (Cl. 62—115)

This invention relates to refrigerating systems in general and in particular to such systems adapted for use on vehicles, whether of the road or rail type.

In certain types of vehicles it is highly advantageous to use a refrigeration equipment having a continuously running prime mover of any suitable type, such as an internal combustion engine. Due to the fact that refrigeration demands on the equipment are intermittent, it has been necessary in the past to provide heavy and expensive couplings, either of the electrical or centrifugal clutch type, in order that the compressor may be disconnected and will work only during such times as refrigeration is required, while the prime mover may run continuously. It is an object, therefore, of the present invention to provide a refrigeration system in which the heavy and expensive couplings between the prime mover and the compressor may be eliminated.

A further object of the invention is the provision of a refrigeration system in which the prime mover and compressor may run continuously, while the compressor will accomplish useful work only at intermittent intervals and then only upon demand.

A still further object of the invention is the provision of a refrigeration system having a continuously running prime mover and a compressor in which the compressor may be loaded and unloaded automatically in accordance with predetermined pressure conditions existing within the system.

A yet further object of the invention is the provision of a refrigeration system having a condenser, the cooling capacity of which may be automatically increased upon and in accordance with an increase of pressure in the system beyond a predetermined value.

These and other objects of the invention will be apparent to persons skilled in the art from a study of the following description and accompanying drawings, in which

Figure 1 is a perspective view of the major portion of the system;

Fig. 2 is a perspective view of the remaining portion of the system and when taken together with Figure 1 discloses substantially the entire refrigerating system, and

Fig. 3 is a schematic wiring diagram disclosing the electrical connections for the system.

Referring now to the drawings in detail, it will be seen that the system alone has been illustrated without any particular reference to its position or location in the vehicle, but as is cus-

tomary with systems of this general type the heavy driving and condensing portion will be located as low as possible in the vehicle, while the cooling unit will be placed within the vehicle at any available portion thereof. The main parts of the system illustrated consist of a compressor C connected to a prime mover E, which is also connected to a drive generator G. The usual engine radiator R is provided for dissipating the heat generated by the internal combustion engine, while condenser H is connected in the system for dissipating the heat extracted from the vehicle by the cooling and ventilating unit V (see Fig. 2) located in the vehicle. In the present instance the engine has been illustrated as of the internal combustion type but it is obvious that any prime mover of a different type might be utilized without in any way affecting the operation of the system. The engine illustrated is of the automotive type having cylinder block 2 in which are reciprocally mounted pistons connected to the crank shaft, which is in turn connected to shaft 4 upon which are mounted a plurality of pulleys 6 and 8. In order to cool the engine and dissipate the heat therefrom conventional connections 9 are made between the engine cylinder block and the radiator R previously referred to. The pulleys 6 receive belts 10 which transmit the power from the engine to pulleys 11 mounted on compressor crank shaft 12. The compressor crank shaft carries any suitable number of pistons reciprocating in cylinder block 14 and provided with the necessary and customary valves by means of which gaseous refrigerant may be compressed to a sufficient degree that when cooled by the condenser it will become liquid. The pulley 8 mounted on the engine crank shaft is connected by means of belt 15 to pulley 16 mounted on the end of an armature shaft of the generator G. The engine generator and compressor are provided with suitable frame and base arrangements B by means of which they may be mounted upon a supporting structure preferably forming a rigid part of the vehicle.

Gaseous refrigerant after being compressed in the compressor may escape from the cylinder block through connection 18 to high pressure outlet pipe 19 which is connected through a discharge cutoff valve 20 located intermediate the compressor and an oil separator 22. The oil separator, which is of an approved type, is provided adjacent its bottom portion with an oil drain connection 23 connected by means of piping 24 to an oil float 26, which is in turn connected by piping 27

to a connection 28 on the compressor crank case. Through this piping and oil float oil separated from the gaseous refrigerant in the separator is collected in the oil float chamber and after it has reached a certain height is discharged back to the compressor crank case. The gaseous refrigerant after passing through the oil separator and giving up its oil passes out of the separator through connection 30 and pipe 32 to the condenser coil structure for dissipation of the heat of compression and to be sufficiently cooled to condense into a liquid. The pipe 32 has interposed therein intermediate the oil separator and condenser a check valve 33 which is so positioned as to prevent return flow of refrigerant from the condenser to the oil separator while permitting unrestricted flow of the refrigerant from the separator to the condenser. After the gaseous refrigerant has been condensed to a liquid in the coils of the condenser H such liquid is drained off through piping 34 into a liquid receiver 36. The liquid receiver is provided with a sealed in glass inspection opening 37 in order that the refrigerant liquid level may be determined and it is also provided with a purge valve 38 by means of which liquid refrigerant may be withdrawn from the system prior to making repairs to the system. Liquid from the receiver is withdrawn through pipe 39 to the evaporator coils (not shown) located in the cooling and ventilating unit V. The pipe 39 has interposed therein a pair of manual valves 40 and 41 located on either side of a strainer 42, which strainer will prevent any foreign matter from reaching the evaporator coils. In case the strainer becomes clogged closing the valves 40 and 41 will permit the removal of the strainer from the system without necessity for removing the refrigerant therefrom. The fluid flowing in pipe 39 to the evaporator coils can only reach such coils after passing normally open refrigerant control valve FV, preferably located in the pipe 39 adjacent the evaporator coils and quite close to the expansion valves 44. These expansion valves are of any approved type but preferably of the type which will insure maximum efficiency in the expansion of the refrigerant from the liquid to the gaseous state, thus providing maximum efficiency for the evaporator coils. After the gaseous refrigerant in the evaporator coils has absorbed heat from the vehicle air circulated through the cooling unit, such gaseous refrigerant may return directly to the compressor through piping 46. The gaseous refrigerant flowing from the evaporator coils to the compressor must pass through connection 47, check valve 48, manual control valve 49 and suction line strainer 50. The check valve 48 permits uninterrupted flow of refrigerant from the evaporator coils to the compressor, but will prevent return flow of refrigerant from the compressor to the evaporator coils. The suction line or return pipe 46 is connected to the compressor by connector 52 and is also provided with an additional connector 53 joined by pipe 54 to a gauge manifold 55. The pipe 54 is connected to the manifold through manual valve 56, permitting entrance of refrigerant into the manifold in order that the pressure in the suction line may be indicated on low pressure gauge LP and also permitting the charging of the system through charging connection 58.

In order that the compressor may be made to assume or be relieved of load pipe 60 is joined to the suction line connector 52 and extends from such connector to a T 61. From this T pipe 62 leads directly to a second T 63 and this pipe has interposed therein a manual cutoff valve 64. The

T's 61 and 63 are joined together by means of piping 66 in which is interposed cut-off valves 67 and an electrically controlled by-pass valve SV. The pipe 69 connects the T 63 with the connector 30 adjacent the oil separator, thus it will be seen that the portion of the pipe between the by-pass valve SV and the oil separator is a high pressure line, while the portion of the piping between the by-pass valve and the compressor is normally subjected to low pressures. The manual control valve 64 and pipe 62 is provided merely to permit manual by-passing of refrigerant around the electrically controlled by-pass valve SV, but normally the valve 64 will be closed and control of refrigerant flow given over to the automatic valve SV.

For certain control purposes pipe 70 is connected into the head of the compressor and extends directly to the gauge manifold through manual valve 72, thereby permitting reading of the pressure in the cylinder head by observation of high pressure gauge HP. The pipe 70 is provided with two connectors 73 and 74. The connector 73 is joined by pipe 76 to a water regulating valve 77, which valve will control flow of water to the condenser coils as will later be described. The connector 74 is joined by pipe 78 to a high and low pressure switch 80 which is in turn connected by pipe 82 to the connector 47 in the low pressure or suction line intermediate the check valve 48 and the evaporator coils. The high and low pressure switch is of any approved type but in general consists of a diaphragm subjected on opposite sides to different pressures and movable under variation in pressures to complete contacts in an electric circuit.

The cooling capacity of the condenser may be increased by permitting water to flow thereover and to this end water storage tanks 84 are provided, which tanks may be filled through piping 85, with the two tanks interconnected by means of pipe 86. One of the tanks is provided with an outlet to which is connected a pipe 87 joined to cutoff valve 88 and strainer 89 which is interposed between the cutoff valve and the water regulator valve 77 previously referred to. Normally the cutoff valve 88 is open and water may flow from the storage tanks through the strainer and under certain conditions of operation past the regulator 77 into pipe 90 located above the condenser and adapted to allow flow of water over the condensing surfaces of condenser H. Moist air passing over the evaporator coils will, of course, be condensed in the ventilating and cooling unit and such condensed moisture is drained from the unit through drain pipe 92 and trap 93, with the discharge being made either outside of the vehicle or if desired into the water storage tanks 84. In the previous description in which reference was had to various pipes, valves, etc., of certain types it is intended that such terms be interpreted broadly and that piping as referred to mean by any type of connection permitting flow and control of gaseous or liquid refrigerant, while the term valves will refer to any type of mechanism for control of fluid flow.

Referring now to Figure 3, which discloses the electrical connection of the various parts of the system, it will be seen that a storage battery 94 has been provided preferably having its positive side grounded and connected to ground wire 95. The negative side of the battery is connected through supply lines 96 to various parts 75 of the system and to equipment panel 97. In

order to control starting of the engine an approved type of starting box 98 is provided. This box is formed with contacts 99 adapted to be bridged by contactor 100 and complete a circuit from supply line 96 through the field winding 101 of starting motor SM which is connected to the ground line 95. The starting box is provided with contactor closing coil 102 connected to the ground line and through circuit breaker 103 to a pair of starting switches 104 adapted to bridge contacts 105, thus completing the circuit through the coil 102 from the supply line 96 to the ground line. As soon as the coil 102 has been energized by closing of the starting switches contactor 100 bridges contacts 99 supplying current to the starting motor and to a coil 106 which operates a choke valve (not shown) on the engine. In completing the circuit to the starting motor and choke operating coil a holding circuit is completed through holding coil 108 which will assist coil 102 in holding the contactor 100 in contact bridging condition. As soon as the engine has started, it will immediately come up to idling speed causing the generator G to develop full voltage which will be impressed through connection 110 upon kick-out coil 112 located in the starting box. Energization of this kick-out coil will cause release of the contactor 100, thus opening the circuit through the starting motor and holding coil 108 and causing the starting motor and choke control coil to cease operation. The generator G is of the shunt type having field winding 114 connected to the ground line and to the equipment panel 97 upon which is mounted the customary voltage and current control, by means of which the excitation of the generator is controlled and the amount of current supplied to the storage battery is limited. The controls in the equipment or control panel are so set that when the engine is running either idle or at full speed the generator will develop full voltage for operation of auxiliary equipment and for charging the storage battery. In order to circulate air from the vehicle space through the evaporator coils a blower motor BM of the series type having field coil 116 is connected to the ground wire and to a contact 118 located adjacent a contact 119 joined to the supply line 96 and which contacts are adapted to be bridged by a contactor 120. The contactor 120 is controlled by coil 122 connected by wire 123 to the ground line and by wire 124 to the negative side of the generator. In this manner as soon as the generator has reached its full voltage output contactor 120 will close completing the circuit and causing the blower motor to operate, thus the blower motor will operate at all times that the prime mover is functioning. Shunt wire 128 is connected to the supply side of the blower motor circuit and to a contact 130 of vehicle thermostat 132 adapted to close when the vehicle temperature is lowered to a predetermined value, thus completing a circuit through the refrigerant control valve FV and closing the same to stop flow of refrigerant to the evaporator coils. The high and low pressure switch 80 previously referred to is provided with contacts 140, one of which is connected to the ground line, while the other is connected to a coil 142 joined to the shunt supply line 128. Upon closing of contacts 140, due to pressure changes in the pressure switch, a circuit will be completed from supply 128 through coil 142 and contacts to the ground line, thus energizing the coil and causing contactors 144 to bridge the contacts 146 and

147. Bridging of the contacts 146 and 147 will complete a circuit from the supply line 128 to the ground line through the by-pass valve SV and idling control arrangement 148 mounted on the engine adjacent the carburetor. Energization of the valve SV and the engine idling control will cause opening of the valve SV permitting flow of refrigerant between pipes 69 and 60, while at the same time causing the engine to return to idling speed. The engine idling control mechanism is so arranged that when no current is flowing through the coil 150, then the engine throttle will be wide open and the engine operating at full speed. However, as soon as the coil is energized for any reason due to operation of the pressure switch condition, the engine throttle will be promptly moved to an idling position. Ignition current to the engine is provided by magneto MA by circuits (not shown) and the engine may be stopped when desired by moving the starting switches 104 from the starting position to a stopping position in which they bridge contacts 160 causing the magneto to be grounded.

The operation of the system is as follows and assuming the system to be in a shut down condition: Movement of the switches 104 into position to bridge contacts 105 will energize coil 102 moving contactor 100 into position to bridge contacts 99, causing the starting motor to crank the engine and at the same time hold the choke in position to supply a rich mixture to the cylinders. As soon as the engine has started to run it will immediately reach at least idling speed causing the generator to develop full voltage with the result that kick-out coil 112 will trip contactor 100 breaking the circuit to the starting motor and choke control. The engine is now operating at least at idling speed causing the generator to develop full voltage which will be supplied through the connections to coil 122 causing contactor 120 to bridge contacts 118 and 119 and causing blower motor BM to start operation. Operation of the blower motor will cause air to be moved through the evaporator coils in the cooling and ventilating unit V and this blower motor will operate at all times that the engine is operating at such speed as to cause the generator to develop full voltage. After long periods of shut down the pressure relation existing between pipes 78 and 82 may and usually will be such as to cause the contacts 140 to be opened, therefore, preventing any completion of a circuit to the by-pass valve SV or engine idling control mechanism. The engine, therefore, will immediately upon starting come up to full speed and will continue at such full speed until such time as the compressor has pumped sufficient refrigerant to reduce the pressure in the suction line 46 to approximately ten pounds per square inch or any similar predetermined value. Lowering of the suction pressure will cause the high and low pressure switch to function closing contacts 140, energizing coil 142 and completing through contactors 144 circuits to the by-pass valve SV and engine idling control 148. Energization of the idling control will immediately bring the engine to idling speed, while energization of by-pass valve SV will permit refrigerant pumped by the compressor at the idling speed of the engine to circulate through pipes 19, oil separator 22, pipe 69, valve SV, pipe 66 and 60 on the suction side of the compressor. The engine compressor and blower motor will continue to function with the engine at idling speed until such time as

the temperature within the vehicle reaches a point warmer than is desired.

As soon as the vehicle temperature rises above the desired level thermostat 132 will open breaking the circuit to the refrigerant control valve FV and permitting the same to open. Opening of the refrigerant valve FV will allow liquid refrigerant to flow from the liquid receiver 36 through pipes 39 and expansion valves 44 to the evaporator coils causing the coils to be chilled. Chilling of the coils together with movement of the vehicle air thereover by the blower motor will cause the refrigerant to pick up the heat units from the vehicle air and this heated refrigerant, which is now in a gaseous state, will flow from the evaporator coils into suction line 46 and into the compressor where it will be compressed and fed through the high pressure line 19 to the oil separator and by way of pipe 32 to the condenser H and back to the liquid receiver in a liquid form. Shortly after the thermostat 132 opens causing refrigerant to be supplied to the evaporator coils, the pressure within the suction line 46 will rise and through pipe 82 connected to the high and low pressure switch will cause such switch to move breaking contacts 140. Breaking of the contacts will, of course, deenergize coil 142 breaking the circuit to by-pass valve SV and engine throttling control 148. Breakage of these circuits will cause the by-pass to close preventing any further flow of refrigerant through the by-pass circuits while at the same time causing the engine to be speeded up to its full speed. With the engine operating at its full speed the compressor will maintain a relatively low suction pressure and will transfer the heated gaseous refrigerant from the low pressure suction line to the high pressure line for extraction of the heat units in the condenser and return of the refrigerant to the liquid receiver.

As soon as the vehicle temperature has been lowered to the desired degree thermostat 132 will close completing a circuit through control valve FV and stopping the flow of liquid refrigerant to the expansion valves 44, but the closing of the thermostat will not immediately affect the operation of the remainder of the system since the engine and compressor will continue to operate at full speed until such time as the suction line pressure in pipes 46 and 82 has been reduced to a sufficiently low point as to cause operation of the high and low pressure switch 80, with the result that the contacts 140 close, opening the by-pass and bringing the engine to idling speed in a manner as has been previously described. In case there is liquid refrigerant in the line between the expansion valve and the control valve FV or in the evaporator coils, such refrigerant will absorb heat and expand causing the suction line pressure to rise, but as soon as this pressure rises contacts 140 open and the engine speeds up and immediately reduces the suction line pressure to the desired low level, thus it will be seen that the arrangement is such as to maintain under normal conditions a definite relation of pressures between the high and low pressure sides of the evaporator coils. Attention is here directed to the fact that the check valves 33 and 48 located in the high and low pressure lines respectively will function as soon as the by-pass valve SV opens to prevent reverse flow of refrigerant in the piping. In other words, when the system is operating normally there are two pressure sides existing, a low pressure side extending from the expansion valves to the piston

of the compressor and a high pressure side extending from the piston of the compressor and including the liquid receiver, condenser and oil separator. When the system is operating with the by-pass valve open there are three pressure areas existing, the first of which is a high pressure area extending from the check valve 33 to the control valve FV and including the bulk of the refrigerant positioned in the condenser and receiver. The second of these areas is one of intermediate pressure and may be considered the by-pass circuit and extends from check valve 33 to check valve 48 and includes therein the compressor, oil separator and by-pass valve SV which is open permitting the pressures on either side of the compressor piston to be substantially equal, thus unloading the compressor. The third of these areas is a low pressure area and extends from the closed refrigerant control valve FV to the check valve 48 and including therein the evaporator coils.

Under certain conditions of operation it will be found that the condenser, which is normally of sufficient capacity to extract the heat units absorbed in the evaporator coils, can no longer function efficiently to condense the gas supplied to it and under this condition abnormal head pressures will exist in the condenser compressor. Under these conditions of abnormal head pressures the water regulator valve 77 through its connections 72 and 16 will open, permitting water to flow from the storage tanks over the condenser and wetting the cooling surfaces thereof. Wetting of the cooling surfaces will due to the evaporative cooling increase materially the rate at which heat units may be extracted from the gaseous refrigerant, thus increasing the condensing capacity of the condenser. In case the water storage tanks should on a long run be emptied or even neglected and not filled, a condition may arise in which it is impossible to hold down the head pressures, but in case such a condition arises the excessive pressure will cause the pressure switch 80 to close the contacts unloading the compressor and returning the engine to idling speed until such time as the head pressures have been reduced by condensation in the condenser. Thus it will be seen that by provision of the high and low pressure switch operating on a differential of pressures in the high and low pressure sides of the system any damage to the parts cannot occur, nor can any particularly unbalanced condition of pressures exist as long as the engine is running and as soon as the engine starts running any unbalanced conditions that might exist are promptly corrected. The use of the high and low pressure switch connected as it is to control the by-pass valve will, together with the check valves, prevent any excessive pressure ever existing in the evaporator coils which were not designed to withstand pressure and would be damaged if subjected to an excessive pressure.

From the preceding description of the refrigeration system and its operation it will be seen that the compressor has been more or less directly coupled to the prime mover, permitting the elimination of any clutches or other expensive connections and that the compressor will run at all times that the prime mover is running. Provision of the by-pass valve permits the compressor to run idle at such times it is not needed for cooling purposes or to maintain the proper pressure relations in the system. By permitting the compressor to run idle when not needed an

extremely efficient operation of the system is attained. The provision of the pressure switch connected into the system in the manner described insures the maintenance of safe pressures in the various component parts of the system and this switch will at the same time permit of increasing the cooling capacity of the condenser by controlling the water flow over the condensing surfaces.

While the refrigerating system has been described more or less in detail, it is obvious that various modifications and rearrangements of parts are possible while accomplishing substantially the same results as described. It is, therefore, my intention to utilize all such modifications and rearrangements of parts as will fall within the scope of my invention and as defined by the following claims.

What is claimed is:

1. In a refrigeration system, the combination of a continuously running prime mover, a compressor connected to said prime mover for operation substantially in unison therewith, a refrigerant circuit connected to said compressor and including a condenser and an evaporator, a by-pass valve for loading and unloading said compressor, and pressure responsive means connected to said by-pass valve and operating to control the by-pass valve to provide for loading and unloading of the compressor in accordance with pressure conditions in said circuit, said pressure responsive means also operating to increase or decrease the speed of the prime mover substantially in unison with the loading or unloading of the compressor.
2. In a refrigeration system, the combination of a prime mover, a compressor connected to said prime mover for operation substantially in unison therewith, a refrigerant circuit containing refrigerant and connected to said compressor and comprising a high pressure side and a low pressure side established by said compressor, said high pressure side including a condenser and said low pressure side including an evaporator, a by-pass circuit connecting said high and low pressure sides of the refrigerant circuit and including a by-pass valve for loading and unloading said compressor, and a pressure responsive means connected to said low pressure side and to said high pressure side and operating solely in response to a predetermined differential of pressures in said sides to control said by-pass valve and by-pass circuit to load and unload the compressor, said pressure responsive means also operating to increase or decrease the speed of the prime mover substantially in unison with the loading or unloading of the compressor.
3. In a refrigeration system, the combination of a prime mover, a compressor connected to said prime mover for operation substantially in unison therewith, a refrigerant circuit containing refrigerant and connected to said compressor and comprising a high pressure side and a low pressure side established by said compressor, said high pressure side including a condenser and said low pressure side including an evaporator, a by-pass circuit connecting portions of said high and low pressure sides of the refrigerant circuit adjacent the compressor and including a by-pass valve for loading and unloading said compressor, pressure responsive means connected to said low pressure side and to said high pressure side and operating in response to a predetermined differential of pressures in said sides to control said by-pass valve to establish the by-pass circuit
- 5 and unload the compressor, said pressure responsive means also operating to increase or decrease the speed of the prime mover substantially in unison with the loading or unloading of the compressor, and means preventing the interchange of refrigerant between the by-pass circuit and those portions of said high and low pressure sides which include the condenser and evaporator respectively when the by-pass circuit is established.
- 10 4. In a refrigeration system, the combination of a prime mover, a compressor connected to said prime mover for operation substantially in unison therewith, a refrigerant circuit containing refrigerant and connected to said compressor and comprising a high pressure side and a low pressure side established by said compressor, said high pressure side including a condenser and said low pressure side including an evaporator, a by-pass circuit connecting portions of said high and low pressure sides of the refrigerant circuit adjacent the compressor and including a by-pass valve for loading and unloading said compressor, pressure responsive means connected to said low pressure side and to said high pressure side and operating in response to a predetermined differential of pressures in said sides to control said by-pass valve to load and unload the compressor, said pressure responsive means also operating to increase or decrease the speed of the prime mover substantially in unison with the loading or unloading of the compressor, and automatically operating means preventing the interchange of refrigerant between the by-pass circuit and those portions of said high and low pressure sides which include the condenser and evaporator respectively when the by-pass valve is open and the compressor unloaded.
- 15 5. In a refrigeration system, the combination of a continuously running prime mover, a compressor connected to said prime mover for operation thereby, a refrigerant circuit charged with refrigerant and connected to said compressor, said compressor operating to maintain a high pressure side and a low pressure side in the circuit, said high pressure side including a condenser and a refrigerant control valve and said low pressure side including an evaporator, a by-pass circuit connecting said high and low pressure sides of the refrigerant circuit and including a by-pass valve for loading and unloading said compressor, a thermostat responsive to temperature changes caused by said evaporator and operating to control said refrigerant control valve and the flow of refrigerant to the evaporator, and pressure responsive means connected to said refrigerant circuit and operating to control the by-pass valve to load and unload the compressor, said pressure responsive means operating irrespective of the thermostat to maintain a substantially constant relation between said high and low pressure sides, said pressure responsive means also operating to increase or decrease the speed of the prime mover substantially in unison with the loading or unloading of the compressor.
- 20 6. In a refrigeration system, the combination of a continuously running prime mover, a compressor connected to said prime mover for operation thereby, a refrigerant circuit charged with refrigerant and connected to said compressor, said compressor operating to maintain a high pressure side and a low pressure side in the circuit, said high pressure side including a condenser and a refrigerant control valve and said low pressure side including an evaporator, a by-

pass circuit connecting said high and low pressure sides of the refrigerant circuit and including a by-pass valve for loading and unloading said compressor; a thermostat responsive to temperature changes caused by said evaporator and operating to control said refrigerant control valve and the flow of refrigerant to the evaporator, and pressure responsive means connected to said refrigerant circuit and operating to control the by-pass valve to load and unload the compressor, said pressure responsive means operating independently of the thermostat to limit the pressure in the high pressure side to a safe value and to increase or decrease the speed of the prime mover substantially in unison with the loading and unloading of the compressor.

7. In a refrigeration system, the combination of a continuously running prime mover, a compressor connected to said prime mover for operation thereby, a refrigerant circuit charged with refrigerant and connected to said compressor, said compressor operating to maintain a high pressure side and a low pressure side in the circuit, said high pressure side including a condenser and a refrigerant control valve and said low pressure side including an evaporator, a by-pass circuit connecting said high and low pressure sides of the refrigerant circuit and including a by-pass valve for loading and unloading said compressor, a thermostat responsive to temperature changes caused by said evaporator and operating to control said refrigerant control valve and the flow of refrigerant to the evaporator, and pressure responsive means connected to said refrigerant circuit and operating to control the by-pass valve to load and unload the compressor and to substantially simultaneously therewith increase or decrease the speed of the prime mover, said pressure responsive means operating independently of the thermostat to limit the pressure in the high pressure side to a safe value, and additional pressure responsive means connected to the high pressure side and operating to reduce the pressure in the high pressure side as it approaches the limiting safe value.

8. In a refrigeration system, the combination of a continuously running prime mover, a compressor connected to said prime mover for operation thereby, a refrigerant circuit charged with refrigerant and connected to said compressor, said compressor operating to maintain a high pressure side and a low pressure side in the circuit, said high pressure side including a condenser and a refrigerant control valve and said low pressure side including an evaporator, a by-pass circuit connecting said high and low pressure sides of the refrigerant circuit and including a by-pass valve for loading and unloading said compressor, a thermostat responsive to temperature changes caused by said evaporator and operating to control said refrigerant control valve and the flow of refrigerant to the evaporator, and pressure responsive means connected to said refrigerant circuit and operating to control the by-pass valve to load and unload the compressor and to substantially simultaneously therewith in-

crease or decrease the speed of the prime mover, said pressure responsive means operating independently of the thermostat to limit the pressure in the high pressure side to a safe value, and additional pressure responsive means connected to the high pressure side and operating to reduce the pressure in the high pressure side as it approaches the limiting safe value, said additional pressure responsive means increasing the cooling effect of the condenser by causing water to flow therover.

9. In a refrigeration system, the combination of an evaporator, a condenser, a prime mover, a compressor connected to said prime mover for operation substantially in unison therewith, a refrigerant circuit containing refrigerant and connected to said compressor and comprising a high pressure side and a low pressure side established by said compressor, said high pressure side extending from the compressor to the evaporator and including the condenser and said low pressure side extending from the compressor to and including said evaporator, a by-pass circuit including the compressor and portions of said high and low pressure sides of the refrigerant circuit adjacent the compressor and also including a by-pass valve for controlling the by-pass circuit thereby loading or unloading the compressor, pressure responsive means connected to said low pressure side adjacent the evaporator and to said high pressure side adjacent the compressor, said pressure responsive means operating in response to a predetermined differential of pressures in said sides to control the operation of said by-pass valve, and independent means in said high and low pressure sides preventing the interchange of refrigerant between the by-pass circuit and the condenser or evaporator when the by-pass circuit is established, the means in said high pressure side being located between the condenser and the connection of the pressure responsive means to the high pressure side whereby said pressure responsive means is subject at all times to the pressure existing in the high pressure side adjacent the compressor.

10. In a refrigeration system, the combination of an evaporator, a condenser, a prime mover, a compressor connected to said prime mover for operation substantially in unison therewith, a refrigerant circuit containing refrigerant and connected to said compressor and comprising a high pressure side and a low pressure side established by said compressor, said high pressure side extending from the compressor to the evaporator and including the condenser, and said low pressure side extending from the compressor to and including said evaporator, and means for establishing under predetermined conditions an intermediate pressure circuit including the compressor and portions of the high and low pressure sides adjacent thereto, said means including a by-pass valve for connecting said high and low pressure sides and check valves for isolating said intermediate pressure circuit from the remainder of the high and low pressure sides of the system.

HERBERT D. EUWER.
